UNITED STATES PATENT OFFICE.

BURR B. BLOOD, OF CHICAGO, ILLINOIS, ASSIGNOR, BY MESNE ASSIGNMENTS, TO JEWEL PHONOPARTS COMPANY, OF CHICAGO, ILLINOIS, A CORPORATION OF ILLINOIS.

REPRODUCER FOR PHONOGRAHS.

Application filed June 24, 1920. Serial No. 391,298.

To all whom it may concern:

Be it known that I, BURR B. BLOOD, a citizen of the United States, and a resident of Chicago, in the county of Cook and State 5 of Illinois, have invented a certain new and useful Improvement in Reproducers for Phonographs, of which the following is a description, reference being had to the accompanying drawing, which forms a part 10 of my specification.

My invention relates to an improvement in reproducers or sound-boxes for phonographs and pertains more especially to the flexible diaphragm and its mounting; the 15 object of the invention being to provide a construction wherein the diaphragm will have a greater vibrating portion and a more uniform flexing area whereby the tone quality of the reproducer will be greatly 20 enhanced.

The construction and its advantages will be readily comprehended from the following detailed description of the accompanying drawing wherein:—

25 Figure 1 is a front elevation of my improved reproducer with a portion broken away and shown in section.

Figure 2 is a cross sectional view taken on the line 2—2 of Figure 1 looking in the 30 direction of the arrows.

Figure 3 is an enlarged sectional view, in perspective, taken substantially on the line 2—2 of Figure 1, but with the flexible diaphragm, stylus bar and front wall or ring 35 member removed; the figure merely illustrating the main shell portion or rear wall of the reproducer-casing.

Figure 4 is a sectional view, in perspective, of the flexible diaphragm, illustrating 40 the lower or inner side thereof.

My invention contemplates a flexible diaphragm, preferably made of a chemical composition rather than of mica; and in the specific exemplification of the invention it 45 comprises a diaphragm or disc 10 of a diameter commensurate with the inside diameter of the casing-ring or member 11 of the reproducer-shell. The diaphragm is of suitable thickness but with a portion somewhat removed from the periphery made of less thickness, as indicated at 12, see Figures 2 and 4. In other words, the diaphragm 10, in the preferred form, is of equal thickness throughout, except for the reduced portion 50 12 which is adapted to come within the area

or circle described by the inwardly disposed peripheral flange 13 of the ring or front shell portion 11 of the reproducer. The reduced portion 12 in the construction illustrated is shown formed by providing the 60 lower or what may be termed the inner surface of the diaphragm, with an annular groove of comparative width and thereby providing an annular central portion 14 to which the stylus bar 15 is secured in the 65 usual manner.

By providing the diaphragm with the kerfed or reduced portion 12 at the place indicated, it leaves a marginal portion 16 on the diaphragm preferably of equal thickness with the central portion 14; the marginal portion 16 being of width substantially equal to the width of the kerfed or flanged portion of the ring or shell section 11. The marginal portion 16 is intended 70 to be clamped between the rear wall or main section 17 of the reproducer and the front or ring section 11; the diaphragm being preferably clamped and held in place by means of suitable rubber rings or gaskets 80 18, 18 disposed on opposite sides of the flexible diaphragm; that is to say, one rubber ring or gasket 18 is arranged on the rear wall or main section 17 of the reproducer, while the other rubber ring or gasket 18 is 85 mounted beneath the flange 13 of the ring section 11 of the reproducer, so that when the ring section 11 is properly secured to the back or main section 17, by means of the screws 19, the rubber rings or gaskets 18 90 will be compressed against the flexible diaphragm 10.

The marginal portion 16 of the flexible diaphragm is of width to adapt it to extend beyond the point where the rubber rings or 95 gaskets 18, 18 contact therewith and therefore extend into the kerfed portion of the ring or shell section 11; and this marginal portion 16, at a point intermediate of the rubber rings or gaskets 18, and the periphery thereof, preferably has its lower surface provided with an annular groove 20, see Figure 4. The groove 20 is shown as preferably V-shape in cross-section and is disposed at a point where it will register 100 with and therefore receive an annular rib 21, also preferably V-shape in cross-section, which is formed integral with the rear wall or main section 17 of the reproducer.

In has been found in practice, that the 110

flexible diaphragm, especially where it is made comparatively thin, has a tendency to buckle when the rubber rings or gaskets are placed under compression; this buckling or bowing of the diaphragm, of course, greatly interfering with its free vibratory or flexing action which is induced by the vibration of the stylus bar. It is apparent that the buckling or bowing of the diaphragm will induce a much stiffer action and therefore result in a considerable loss of the finer tones or vibrations. In providing the flexible diaphragm with the groove 20 and one shell or section of the reproducer with a correspondingly formed rib, adapted to register with and become seated in the groove of the diaphragm, any tendency or possibility of the flexible diaphragm to buckle or become distorted will be entirely eliminated, as the rib 21 will prevent any movement or crowding of the flexible diaphragm into the area described by the inner circumference of the ring section of the reproducer.

25 In the particular exemplification, the screw-receiving holes 22 formed in the rear wall section of the reproducer are shown located at points registering with the annular rib 21, so that the diaphragm is likewise illustrated provided with screw-receiving holes 23 for the passage of the screws 19 whereby the two shell sections of the reproducer are secured together. It is apparent, however, that the screw-receiving openings 35 22 and 23 in the rear wall section 17 and flexible diaphragm 10, respectively, need not be arranged at the particular point indicated and furthermore the exact formation of the reproducer shell sections may be somewhat varied from the construction shown; while at the same time the reduced or more readily flexing portion of the flexible diaphragm may also be obtained in a somewhat different manner from that shown and described.

40 45 These modifications and other slight modifications may be made in details of construction without departing from the spirit of my invention.

Having thus described my invention, what I desire to secure by Letters Patent is—

1. In a reproducer of the character described, a casing composed of a main or back member and a front or ring member, one of said members being provided with an annular rib, both members being removably secured together, and a flexible diaphragm, the peripheral margin whereof is adapted to

be clamped between the two members of the casing, the peripheral margin of the diaphragm adapted to be clamped between the 60 casing-members being provided with an annular groove of configuration substantially similar to the cross sectional configuration of the annular rib on said casing member and adapted to receive the said annular rib. 65

2. A reproducer of the character described, comprising a casing composed of a main or back member and a front or ring member provided with a kerf or under-cut and adapted to be removably secured to the main member, one of said members adjacent the periphery thereof being provided with a projection on its inner surface, and a flexible diaphragm adapted to extend into said kerf or under-cut of the ring member and to be 70 clamped between both casing members, the marginal portion of the diaphragm being recessed to receive the projection on the inner surface of the casing member whereby buckling or crowding of the diaphragm within 75 the ring member is prevented. 80

3. In a reproducer of the character described, a casing composed of a main or back member provided with an annular rib adjacent the periphery thereof and a front or ring member, the latter being provided with an inwardly disposed annular flange and with a diaphragm-receiving recess, the two members being removably secured together, a flexible diaphragm adapted to be seated in 90 the recess of said ring member and to be clamped between both casing members, the flexible diaphragm adjacent its perimeter provided with an annular groove adapted to receive the annular rib formed on the main 95 member of the casing. 100

4. A reproducer of the character described, comprising a casing composed of a main or back member provided with an annular rib, V-shape in cross-section, disposed adjacent the periphery thereof, and a ring member removably secured to the main member, a flexible diaphragm adapted to be clamped between the casing-members, and provided in its marginal portion with an annular groove, V-shape in cross-section, adapted to receive the annular rib on the main member of the casing whereby buckling of the diaphragm within the ring member of the casing will be prevented.
